UNITED STATES PATENT OFFICE

139,299

DESIGN FOR A BLADE FOR PAPER BOX OPENER

Lewis Walters, New York, N. Y.

Application August 21, 1944, Serial No. 114,952

Term of patent 14 years

(Cl. D22—3)

To all whom it may concern:

Be it known that I, Lewis Walters, a citizen of the United States of America, residing at New York, in the county of New York and State of New York, have invented a new, original, and ornamental Design for a Blade for Paper Box Opener, of which the following is a specification, reference being had to the accompanying drawing, forming a part thereof.

In the drawing:

blade for paper box opener showing my new design,

I claim:

The ornamental design for a blade for paper box opener, as shown.

LEWIS WALTERS.
